COMBINED FOLDING AND FEEDING STITCHING DEVICE

Filed Sept. 7, 1940

UNITED STATES PATENT OFFICE

2,316,061

COMBINED FOLDING AND FEEDING
STITCHING DEVICE

Bernard Furer, Brooklyn, N. Y., assignor to
Picardy Mills, Inc., Brooklyn, N. Y., a corpora-
tion of New York

Application September 7, 1940, Serial No. 355,705

2 Claims. (Cl. 112—136)

My invention relates to a combined folding and guiding stitching device and its novelty consists in the adaptation and arrangement of parts as will be more fully hereinafter pointed out.

The folding and feeding of a material and a braid or piping and stitching them together, whether it be a braid or piping on a dress or a glove or similar article, has heretofore required three operations whereas my device eliminates two operations and does the complete work continuously in one operation and with a unitary structure.

Under the prior art it was necessary to first stitch the braid or piping flat to the edge of the fabric on one side and then turn back both the fabric edge and the piping thereover and again stitch it through both the turned fabric edge and turned piping and thereafter trim the edge of the piping with shears by hand.

This method which is still generally used, particularly in connection with gloves as well as with dresses, gives an unsatisfactory finished edge as the hand trimming by shears is always irregular so that the finished article is seldom uniform.

My device is a single unit; adapted to be rigidly mounted on the presser bar of a sewing machine of usual factory type so that it guides the braid or piping through so as to fold each edge back on the piping with the upper edge overlapping the lower edge and then as the fabric or glove edge is fed into my device it is turned back on itself to make a completed edge and it feeds therethrough on top of the folded piping continuously under the presser foot by means of the usual feed dog of the sewing machine. The braid or piping is fed through my device automatically once it has been started therethrough and the fabric or glove edge is fed into my device by hand and the regular feed dog of the sewing machine feeds this combined piping and turned edge of the fabric in the usual way under the threaded needle so that they are stitched together continuously along the edge of the fabric or glove to its end when another piece of fabric or glove is fed in as described, the feeding of the double turned piping being automatic when once started.

My device thereby insures the elimination of two steps and the formation of a uniformly turned and stitched piping along the entire edge of the glove or fabric whereby a more perfect article is secured and a very great saving in time and cost is made because of the complete elimination of two operations.

Referring to the drawing

Figure 1 is a perspective looking at the inner side of the head of a sewing machine showing my device, with material therein, rigidly secured to the presser bar of said machine and the rest of the sewing machine being broken away for convenience in illustration.

Figure 2 is a top plan view of my folding and guiding device.

Figure 3 is a perspective of the assembling of the piping and glove or fabric edge showing a portion completed and the piping and glove or fabric edge coming together for stitching.

Figure 4 is a cross section on the line 4—4 of Figure 3 of the completed stitched fabric edge and piping.

Figure 5 is a cross section on the line 5—5 of Figure 2 looking in toward the right.

Figure 6 is a perspective of a portion of my device as shown in Figure 2 with portions broken away so as to show the folding and feeding of the piping.

Figure 7 is a side elevation looking in from the upper side of Figure 2, the ends being broken away for convenience in illustration.

In the drawing 10 is a stitching table of the usual factory or manufacturing type of sewing machine on which is a head portion 11 of usual construction carrying the regular presser bar 12 positioned by lever 13 in the usual manner and a feed dog 14 mounted and oscillating in the usual manner in said table 10.

My single piece continuous folding and guiding device 15 has a slotted portion 16 which is adapted to slide over said presser bar 12 and be rigidly secured thereto by a set screw 17 and the hole 18 in said folding and guiding device 15 allows needle 19 of usual construction to pass through and stitch in the usual manner the materials held thereunder in said folding and guiding device 15.

In the folding and guiding device 15 there is at one end a downturned lip 32, an open slot 20, an inturned flange 21 which is turned down on one side and an inturned flange 22 which is turned down on the other side so that said flange 22 as it runs inwardly toward the glove or fabric guiding portion 23 will come to a position where it overlaps the flange 21 and has an undeturned guide lip 33 at its outer edge so that as the tape or piping 28 feeds through the edge following the inturned flange 22 and limited by guide lip 33 it will overlap the edge following the inturned flange 21 an exact amount and said overlapped tape or piping 28 will gradually flatten out as

it approaches the glove or fabric guiding element 23. This fabric or glove guiding portion 23 comprises the curved guide or feeding plate 24 which extends at 25 beyond the bracket portion 26 on which said plate 24 is rigidly mounted and a flared circular guide plate 27 runs from said bracket 26 around and over the inner end of said extended plate 25, thereby forming a groove 30 under said extended plate portion 25 whereby the glove or other fabric 29 being fed in by hand by the operator will pass over said plate 24 and the extended end 25 and thrusting against said flare guide 27 will push down under the extended end 25 into said groove 30 thereby turning back on itself as it is fed forward through opening 34 between device 15 and the feed dog 14. In this way the overlapped piping or tape 28 being fed through my device as described will thereby be met by the folded fabric or glove 29 thus being fed so that said folded glove or fabric portion 29 will lay on top of said overlapped tape or piping 28 and as the feed dog pulls them along together through opening 34 in the usual manner they will pass under the operating needle 19 which will stitch them together in this described position continuously.

The operation of my device is simple. The folding and guiding mechanism 15 is first mounted on a presser bar of a sewing machine by means of the slotted portion 16 fitting over said presser bar 12 and being held rigidly thereon by means of set screw 17 and the piping 28 which has been previously fed through 15 and out through opening 34 will be held in position for the operating of the sewing machine head 11 as the lever 13 is pressed down so as to lock said piping 28 under the presser bar 12 and device or foot 15 in the usual manner.

The glove or fabric 29 will be fed by the operator over the feed plate 24 so that the inner edge of said fabric or glove will pass around the extended end 25 of said plate 24 and turn back thereover in groove 30 so that as said folded edge of fabric or glove 29 passes on to the overlapped folded piping 28 under the presser bar 12 and device 15 they will be fed along together uniformly through opening 34 by the oscillation of the feed dog 14, which is set into operation by the regular operation of the sewing machine head 11.

The finished piping 28 mounted on the turned edge of the fabric or glove 29 is shown in Figure 3 stitched together at 31 in their completed condition and the cross section in Figure 4 shows the

said relative positions when completed in their stitched position, 31 designating said stitching.

Many variations may be made in the particular form of my device without departing from the spirit and intent of the same and such variations are included within the scope of my invention.

My device is also adapted to be used as the presser foot on any sewing machine and can be so mounted on the presser bar of any sewing machine by merely adapting the attaching portion 16 to the particular presser bar on which it is mounted.

I claim:

1. In a single piece device, means for rigidly securing said device to a sewing machine presser bar, means for folding and guiding a tubularly formed overlapped folded edge piping therethrough comprising a downturned lip at the outer end, a tubular opening adjoining said lip and an inturned flange adjoining said tubular opening turned down and under on one side and a second inturned flange on the opposite side from said first flange turned down so that it runs inwardly towards a side guiding portion as it overlaps said first flange in an edge turned back on itself, means for folding and guiding a fabric edge therethrough so that said piping is guided in its folded tubular position under said folded fabric edge comprising a side guiding plate and an undercut groove under the inner end of said plate immediately over said inner tubular end opening.

2. In a single piece device, means for rigidly securing said device to a sewing machine presser bar, means for folding and guiding a tubularly formed overlapped folded edge piping therethrough comprising a downturned lip at the outer end, a tubular opening adjoining said lip and an inturned flange adjoining said tubular opening turned down and under on one side and a second inturned flange on the opposite side from said first flange turned down so that it runs inwardly towards a side guiding portion as it overlaps said first flange in an edge turned back on itself, means for folding and guiding a fabric edge therethrough so that said piping is guided in its folded tubular position under said folded fabric edge and fed into said sewing machine and stitched together in said position by said sewing machine feeding and stitching mechanisms comprising a side guiding plate and an undercut groove under the inner end of said plate immediately over said inner tubular end opening.

BERNARD FURER.
